UNITED STATES PATENT OFFICE.

EDWARD B. CRAFT, OF HACKENSACK, NEW JERSEY, ASSIGNOR TO WESTERN ELECTRIC COMPANY, OF NEW YORK, N. Y., A CORPORATION OF ILLINOIS.

TELEPHONE-TRANSMITTER.

1,096,153.

Specification of Letters Patent. Patented May 12, 1914.

Application filed July 9, 1910. Serial No. 571,180.

To all whom it may concern:

Be it known that I, EDWARD B. CRAFT, citizen of the United States, residing at Hackensack, in the county of Bergen and 5 State of New Jersey, have invented a certain new and useful Improvement in Telephone-Transmitters, of which the following is a full, clear, concise, and exact description.

This invention relates to telephone trans- 10 mitters, its object being to provide a simple and inexpensive structure for adjustably se- curing and insulating one of the electrodes thereof.

In accordance with the invention the 15 structure for supporting the electrode com- prises a tubular bolt held in an opening in a piece of the frame of the transmitter, the diameter of the opening being larger than that of the bolt and the bolt being held in 20 central position by means of an insulating washer or washers seated on one or both sides of the frame piece, and secured against lateral displacement. The holes in said washers are of the same diameter as the out- 25 side diameter of the bolt and means, prefer- ably a nut, is provided for clamping the bolt in place. The rear electrode is provided with a stud which is adapted to slip loosely through the hole in the bolt where it is 30 finally held rigidly in place by means of a set screw or other fastening means. Elec- trical connection to the rear electrode may be made by means of a terminal washer clamped between the bolt and frame plate. 35 To prevent the washer from rotating, it may be provided with a raised point or ridge engaging a notch in the underneath side of the bolt head.

The invention will be fully understood by 40 reference to the accompanying drawings, in which—

Figure 1 is a rear elevation, with the cas- 45 ing removed, of a telephone transmitter em- bodying the invention; Fig. 2 is an enlarged fragmentary view in section along the line 2—2 of Fig. 1; and Fig. 3 is a detail sec- tional view of the bridge piece on the line 3—3 of Fig. 1.

In the drawing, the frame 1 of the trans- 50 mitter is provided with the usual mouthpiece 2 and bridge piece 3, a casing 26 serving to cover the working parts and to support the instrument. A diaphragm 4 is seated in the frame 1 but insulated therefrom by a 55 washer 5 which may be of paper, the dia-

phragm having a turned up circumferential flange 6 flattened at its extreme edge. In the center of the diaphragm is a depression 7 adapted to be engaged by the rounded end of a stud 8 which is secured to the front 60 electrode 9 of a granular button unit 10, the radius of curvature of the stud end being slightly greater than that of the depression, so that contact will be made at the perimeter of the depression. The stud 8 has a flange 65 27 forming a shoulder against which the free upturned ends 28 of a spring 11 bear. This spring is held by but insulated from the bridge piece 3 by means of screws 12 and a tapped bar 13, a screw 14 being provided 70 for connecting a wire to make electrical connection with the front electrode.

The back electrode of the granular but- 75 ton 10 is provided with a stud 15 adapted to slip freely through a hole in a tubular bolt 16. This bolt is of smaller diameter than an opening 17 in the bridge piece 3, but is held centrally positioned in said opening and therefore out of contact therewith by means of insulating washers 18, prefer- 80 ably of mica. These washers are seated as shown in depressions on either side of the bridge piece. The bolt is held in place by a nut 19 and electrical connection to the back electrode through the bolt is provided 85 for by a terminal washer 20 lying under the head of the bolt and held in place by it. This washer is prevented from turning with respect to the bolt by means of a notch 21 under the head of the bolt engaged by the 90 washer at a raised point or ridge 22, which is formed in the washer. One of the insu- lating washers 18 is of irregular contour, as shown in Fig. 1, so that when seated in the bridge piece it cannot turn with the bolt 95 and the washer 20 is provided with a raised point 23 engaging a hole in the insulating washer to prevent turning with respect to the bridge piece. A screw 24 is provided for making the electrical connection to the 100 rear electrode.

In assembling the parts of this trans- 105 mitter the tubular bolt 16 and its several washers are put in place and the nut 19 turned until the bolt is held rigidly in place. The granular button unit 10 is then inserted with its stud 15 lying loosely in place and the spring 11 fastened in place with its free ends engaging the shoulder of the stud back of the rim 9. The diaphragm 4 is then placed 110

loosely in its seat against the paper washer 5 and the bridge piece, with the granular button and spring held thereby, fastened securely to the frame 1 with the end of the 5 front electrode stud 8 engaging the depression 7 at the center of the diaphragm. At this time the spring 11 will give somewhat, but will exert the proper pressure against the diaphragm and the position of the dia- 10 phragm in its seat will be adjusted to conform to any slight irregularities in the formation of the bridge and the position of the granular button therein. At the same time the stud 15 of the back electrode will be 15 pushed backwardly and assume its proper position in the bolt opening. Finally the back electrode may be rigidly secured in place by means of the set screw 25.

Having thus described my invention, what 20 I claim is:

1. In a telephone transmitter, the combination of an electrode provided with a stud, a frame piece for holding said electrode in place, a tubular bolt, said frame piece having an opening larger in diameter than said bolt and through which the bolt extends, insulating washers seated in depressions in either side of said frame piece about said opening and adapted to hold said bolt in central position with respect to said opening, means for rigidly clamping said bolt in place in the opening, and means for adjustably fastening said stud in the opening through said tubular bolt.
2. In a telephone transmitter, the combination with an electrode provided with a stud by which it is adapted to be supported and a bridge piece having an opening through which said stud extends, of a tubular bolt fitting over said stud, said bolt being of smaller diameter than the opening in

said bridge piece, insulating washers seated in depressions in either side of said bridge piece about said opening and adapted to hold said bolt in central position away from 45 contact with the walls of said opening, means for clamping said bolt into place, and a terminal washer held in place by and in contact with said bolt.

3. In a telephone transmitter, the combination with an electrode provided with a stud and a frame piece for holding the electrode in place, of a tubular bolt embracing said stud, said frame piece having an opening of larger diameter than the diameter of 50 said bolt, insulating washers seated in depressions in either side of said frame piece about said opening and adapted to hold said bolt in central position with respect to said opening, one of said insulating washers being of irregular shape, means for fastening said bolt in place, a terminal washer held by and in contact with said bolt and provided with a projection engaging said irregular shaped washer.

4. In a telephone transmitter, the combination with an electrode provided with a stud and a frame-piece for holding the electrode in place, of a tubular bolt embracing said stud and insulatively secured in an 70 opening in said frame, and a terminal washer clamped by said bolt to said frame plate, said washer having a projection adapted to fit into a depression in said bolt to prevent rotation of said washer.

In witness whereof, I, hereunto subscribe my name this 7th day of July A. D. 1910.

EDWARD B. CRANE.
